UNITED STATES PATENT OFFICE.

LOUIS B. FULTON, OF PITTSBURG, PENNSYLVANIA, ASSIGNOR TO THE CHAPLIN-FULTON MANUFACTURING COMPANY, OF PITTSBURG, PENNSYLVANIA, A CORPORATION OF PENNSYLVANIA.

FEED-WATER REGULATOR.

SPECIFICATION forming part of Letters Patent No. 770,634, dated September 20, 1904.

Application filed April 4, 1904. Serial No. 201,496. (No model.)

To all whom it may concern:

Be it known that I, LOUIS B. FULTON, of Pittsburgh, in the county of Allegheny and State of Pennsylvania, have invented certain new and useful Improvements in Feed-Water Regulators; and I do hereby declare the following to be a full, clear, and exact description of the invention, such as will enable others skilled in the art to which it appertains to make and use the same.

In feed-water regulators of the type employing controlling-valves, the seating whereof in the feed-line is effected by boiler-pressure, more or less serious difficulties are encountered under adverse conditions. Where there is a great variance in loads and where there is any great variance in the applied heat for steam production, as is found in boilers over heating-furnaces, there is always danger of flooding in the event of boiler-pressure dropping to any material extent, being thereby insufficient to effect the seating of the controlling-valve. To avoid this, it has been sought in some instances to very considerably enlarge the diaphragm of the controlling-valve; but this necessarily increases the cost as well as making the valve quite cumbersome. Furthermore, frequent operations of the controlling-valve have a tendency to vaporize the condensation accumulating in the diaphragm-casing, allowing live steam to come in contact with the diaphragm-rubber, such steam having a tendency to vulcanize and destroy the latter. In feed-water regulators of this class, of which that shown in Letters Patent No. 662,488, issued to me November 27, 1900, is an illustration, the mode of supplying power for closing the controlling-valve is to tap into a steam connection somewhere near the steam-gage, so that the steam passing to the actuating-valve, at such times as it is allowed to do so under the automatic movement of the displacement-body, will act directly upon the column of water of condensation bearing upon the diaphragm of the controlling-valve, and thereby effect the seating of the latter. In addition to the difficulties hereinbefore speci-

fied in boilers exposed to the elements, the column of water actuating the diaphragm-valve being at rest, freezing will occur in cold weather, rendering the machine inoperative.

The object of the present invention is to overcome all of the above-noted objections and difficulties. This, briefly stated, is accomplished by making the seating of the controlling-valve entirely independent of the boiler-pressure—in other words, effecting the seating of such valve by the excess pressure in the feed-line.

The invention will be hereinafter fully set forth and particularly pointed out in the claims.

In the accompanying drawings, Figure 1 shows the general outline of a feed-water regulator embodying my improved means as applied to boilers. Fig. 2 is a view of portions of the pressure-pipe, parts thereof being in section. Fig. 3 is a sectional view of the auxiliary or escape valve. Fig. 4 is a similar view of the controlling-valve. Fig. 5 shows in section the displacement body-casing and the means for operating the auxiliary valve.

As pointed out in my before-noted patent, the controlling-valve 1 is positively seated and unseated by pressures acting in opposite directions, one pressure medium being controlled by means operated by the water in a trap-casing 2. This latter is connected at its top and bottom by pipes 3 and 4 to the water column 5, the internal displacement-body 6 controlling the position of the lever 7, from which it is hung. When the water in the boiler falls sufficiently to uncover pipe 3, steam will enter the trap-casing at the top and displace the water, the body 6 at once lowering, and when sufficient water is supplied to the boiler to submerge the end of pipe 3 the condensation of the entrapped steam will cause the water to again rise in the trap-casing and effect the raising of body 6. When the latter is lowered, its lever 7 unseats an auxiliary or escape valve 8, which is located in a pressure-pipe 9, leading from the diaphragm-casing of the controlling-valve to the top of casing 2.

This latter valve is located, as shown, in the feed-line pipe 10, which opens into the boiler or boilers; but instead of being held to its seat by steam or boiler pressure I provide for 5 the pressure in the feed-line acting against the diaphragm for that purpose. The pressure-pipe 9 is connected to the feed-line pipe 10 by a by-pipe 12, opening into the pressure-pipe just above its connection to the dia- 10 phragm-casing, such connection being taken between the controlling-valve and the source of supply. Within this by-pipe is a stricture-nipple 13, and within a union 14 is a screen 15 to prevent sediment from entering the stricture-nipple and interfering therewith. A globe-valve 16 may be used to cut off com- 15 munication to the diaphragm from the feed-line pipe, as when repairs are necessary. The object of the stricture-nipple is to allow of a 20 continuous circulation within the pressure-pipe when the machine is operated to supply water to the boiler. The outlet of the auxiliary or escape valve is of greater size than the opening in the stricture-nipple, so that when 25 such valve is unseated the diaphragm will be entirely relieved of pressure. The auxiliary valve is normally held to its seat by a spring 17, coupled with the pressure from pipe 9, acting downwardly thereon. When, how- 30 ever, this valve is unseated by the tilting of lever 7, the water from pipe 9 will escape through the outlet 18.

In practice there is always an excess pressure in the feed-line over the boiler-pressure 35 from ten to fifteen pounds. The auxiliary valve being normally seated, the controlling-valve will be likewise held to its seat by the overpressure in the feed-line. When, how- 40 ever, the conditions in the boiler result in the lowering of the displacement-body, the auxiliary valve will be unseated, relieving the pressure on the diaphragm of the controlling-valve and allowing the latter to rise under the pressure of the feed-water coupled with the 45 lifting-spring 19. While the controlling-valve is so unseated and the boiler is being supplied with water, there will be a constant flow through pipe 9. The nipple is struc- 50 tured to such an extent that the loss in heat units, escaping in the hot water and which es- 55 cape keeps up the continuous circulation in the pressure-pipe, is considerably less than the amount of steam which is lost when the controlling-valve is held seated by steam-pres- 60 sure as heretofore practiced. Thus I mate- rially increase the efficiency of the machine.

From what has been said it will be seen that there are many advantages possessed by my invention over the means heretofore known 65 and used, that by means thereof all danger of freezing of the column of water in the pressure-pipe is avoided, the diaphragm cannot be burned out or its usefulness impaired, and there is no danger of flooding the boiler, since 70 the seating of the controlling-valve is entirely

independent of the boiler-pressure, being de- 70 pending entirely upon the excess pressure in the feed-line. If at any time the steam in the boilers falls to a lower pressure than that in the feed-line, the pressure on the diaphragm of the controlling-valve will be sufficient to instantly close the latter, and thereby cut off further supply of water to the boiler. It will also be noted that systems now in operation 75 may at but slight cost be equipped with the present improvements, it being necessary only to cut off the steam connection from the boiler to the auxiliary valve and connect up the by-pipe between the pressure-pipe and feed-line at a point between the controlling-valve and 80 the source of supply.

I claim as my invention—

1. A feed-water regulator comprising a con- 85 trolling-valve located in the feed-line and seated and unseated by pressure in such feed-line acting in opposite directions on such valve, and means, operated by the conditions in the boiler, for directly controlling the pressure acting in one direction on such valve.

2. A feed-water regulator comprising a con- 90 trolling-valve located in the feed-line, a pres- 85 sure-pipe leading to such valve, a connection between the feed-line and such pressure-pipe, and means operated by the conditions in the boiler for relieving the pressure in said pres- 95 sure-pipe, such pressure effecting the seating of such controlling-valve.

3. A feed-water regulator comprising a con- 100 trolling-valve located in the feed-line and seated and unseated by pressure in such feed- 100 line, means for relieving the pressure acting in one direction on such valve, and means for actuating such latter means according to the conditions in the boiler.

4. A feed-water regulator comprising a con- 105 trolling-valve located in the feed-line and seated and unseated by pressure in such feed-line acting in opposite directions, means actuated by the conditions in the boiler for relieving the pressure acting in one direction on such 110 controlling-valve, and means for allowing a continuous circulation, when the valve is unseated, of the water whose pressure serves to seat such valve.

5. A feed-water regulator comprising a con- 115 trolling-valve located in the feed-line, a pres- 115 sure-pipe leading to such valve, a by-pipe con- 120 necting said feed-line to said pressure-pipe, an auxiliary valve in said pressure-pipe, and means actuated by the conditions in the boiler 120 for relieving pressure in said pressure-pipe through said auxiliary valve, the water in such pressure-pipe being allowed to circulate when so relieved.

6. A feed-water regulator comprising a con- 125 trolling-valve located in the feed-line, a pres- 125 sure-pipe leading to such valve, a by-pipe con- 130 necting said feed-line to said pressure-pipe, a stricture-nipple in such by-pipe, an auxiliary valve having an outlet of greater area than 130

the opening of the stricture-nipple, and means actuated by the conditions in the boiler for operating said auxiliary valve.

7. A feed-water regulator comprising a controlling-valve located in the feed-line and having a diaphragm and casing therefor, a pressure-pipe opening into such casing above said diaphragm, a by-pipe connecting said feed-line to said pressure-pipe, so that said controlling-valve will be normally held seated by the pressure in the feed-line, an auxiliary valve in said pressure-pipe, and means for automatically unseating such auxiliary valve, according to the conditions in the boiler, for relieving pressure on said diaphragm.

8. The combination with the feed-line and the controlling-valve having a diaphragm and

casing therefor, of the pressure-pipe opening into said casing, the by-pipe connecting said feed-line to said pressure-pipe, a stricture-²⁰ nipple in said by-pipe, a screen also arranged between said stricture-nipple and the feed-line, an auxiliary valve in said pressure-pipe, and means automatically actuated by the conditions in the boiler for unseating such auxiliary valve, as set forth.

In testimony whereof I have signed this specification in the presence of two subscribing witnesses.

LOUIS B. FULTON.
